(57) **CLAIM**

I claim the ornamental design for a playing surface for spinning top toy, as shown and described.

DESCRIPTION

FIG. 1 is a front view of the playing surface for spinning top toy;

FIG. 2 is a rear view thereof;

FIG. 3 is a left-side view thereof;

FIG. 4 is a right-side view thereof;

FIG. 5 is a top plan view thereof;

FIG. 6 is a bottom plan view thereof;

FIG. 7 is a front, right-side, top perspective view thereof;

FIG. 8 is an exploded top perspective view thereof;

FIG. 9 is an exploded bottom perspective view thereof;

FIG. 10 is a front, right-side, top perspective view of the upper component of the playing surface for spinning top toy, shown separately for clarity;

FIG. 11 is an unshaded front, right-side, top perspective view of the upper component of the playing surface for spinning top toy, shown separately for clarity;

FIG. 12 is a rear, left-side, bottom perspective view of the upper component of the playing surface for spinning top toy, shown separately for clarity; and,

FIG. 13 is an unshaded rear, left-side, bottom perspective view of the upper component of the playing surface for spinning top toy, shown separately for clarity.

Transparent surfaces are shown with diagonal shading, in accordance with 37 CFR 1.152.
